DESIGN FOR A DRESS

Jane Rosener, New York, N. Y.

Application November 14, 1939, Serial No. 88,251

Term of patent 3½ years

To all whom it may concern:

Be it known that I, Jane Rosener, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The design is characterized by the combination on the dress disclosed of the self-material button trimming around the neck and cuffs in association with the two rows of smaller matching buttons extending down the center front and center back of the blouse portion, as shown.

I claim:

The ornamental design for a dress, substantially as shown and described.

JANE ROSENER.
